United States Patent [19]

Flesher et al.

[11] Patent Number: Des. 303,007

[45] Date of Patent: ** Aug. 22, 1989

[54] ELECTROPHORESIS SEQUENCING APPARATUS

[75] Inventors: Robert W. Flesher, Baltimore; Kevin J. Barnes; Robert W. Blakesley, both of Frederick; Robert W. Lynn, Germantown, all of Md.

[73] Assignee: Life Technologies, Inc., Gaithersburg, Md.

[**] Term: 14 Years

[21] Appl. No.: 10,113

[22] Filed: Feb. 2, 1987

[52] U.S. Cl. D24/8

[58] Field of Search .... D24/8, 31, 1.1; 204/299 R, 183.1
